UNITED STATES PATENT OFFICE.

MICHAEL SEGEL, OF NEW YORK, N. Y.

LIGHTING APPARATUS FOR MOTION-PICTURE MACHINES.

1,255,344.

Specification of Letters Patent.

Patented Feb. 5, 1918.

Application filed July 17, 1913. Serial No. 779,419.

To all whom it may concern:

Be it known that I, MICHAEL SEGEL, a citizen of the United States, residing at New York county, city and State of New York, have invented certain new and useful Improvements in Lighting Apparatus for Motion-Picture Machines, of which the following is a clear, full, and exact description.

This invention relates to an improvement in lighting apparatus for motion picture machines particularly. My invention appertains more particularly to arc lights used to cast motion pictures upon a screen and has for an object an improved condenser.

One of the chief objects of my invention is to provide a plurality of condensers which can be moved in position between the arc light and motion picture device.

Figure 1 is a sectional side elevation of an entire lighting system embodying my improvement in condensers.

Fig. 2 is a front view showing the condensers in position with the one reserve condenser carried in readiness to be slid into position as soon as the one in use has become injured.

In the drawings the numeral 1 indicates the usual shutter which is located between the condensers 2 and 3, which are as usual made of glass.

As can be seen in Fig. 1 the condensers are carried in a frame 4 and 5, that is to say, each pair of condensers is carried in an independent frame which frames are slidable in a support 6.

Copies of this patent may be obtained for five cents each, by addressing the "Commissioner of Patents, Washington, D. C."

The object of providing a plurality of sets of condensers is to enable the operator to immediately slide in a new set of condensers should those in use break.

I claim as my invention:

1. In a projecting apparatus having a plurality of sets of condensers mounted in a casing movable in a guideway whereby when one condenser is moved into the line of light, the other condenser is moved out of the line of light.

2. In a projecting apparatus, a casing having a guideway and a frame carrying a plurality of sets of condensers mounted on said casing and adapted for movement in said guideway to position, successive sets of condensers in front of the light course.

3. In a projecting apparatus having a source of light, a guideway, a plurality of sets of condensers mounted in said guideway near said light source, and adapted to be moved in and out of focal axis of the light source, whereby the sets of condensers in front of the arc can be removed by moving the successive sets in front of the light source.

Signed at New York city, New York, this 12th day of July 1913.

MICHAEL SEGEL.
